UNITED STATES PATENT OFFICE.

GEORGE H. KOSTER, OF OAKLAND, CALIFORNIA.

CANDY VENDER.

Application filed September 17, 1924. Serial No. 738,239.

The present invention relates to improvements in vending devices for articles of merchandise and has been particularly designed to be used as a vender for candy. The device to be described in this application may be used in connection with the device described in my co-pending application Serial Number 706,620, and lends itself very readily to such use as will appear from the drawings in this application. The particular object of the present invention is to provide a means by which candy of different kinds may be conveniently displayed in different compartments so as to be inaccessible to a stranger but which compartment may be readily made accessible to the salesman. It is proposed to utilize for this purpose a revolving table or platform having radial partitions thereon forming circumferential compartments which are closed at their outer ends, preferably by means of transparent plates and to provide in conjunction therewith a stationary cover which renders the compartments inaccessible to a purchaser standing outside of the counter on which my device rests, while any one of the compartments may be made to register with an opening disposed in the cover and to be readily accessible for the clerk standing inside of the counter. Further advantages and features of my device will appear as the specification proceeds.

The preferred form of my invention is illustrated in the accompanying drawings in which:—

Figure 1 shows a side elevation of my device with the candy vender of the prior application attached thereto;

Figure 2 a top plan view of the device shown in Figure 1;

Figure 3 a vertical section taken along the line III—III of Figure 2, and

Figure 4 a horizontal section taken along line IV—IV of Figure 1.

While I have shown only the preferred form of the invention, it should be understood that various changes or modifications may be made within the scope of the claim hereto attached without departing from the spirit of the invention. A cross-shaped base 1 is made to rest on any suitable support such as the counter in a candy store. A stem 2 rises vertically from the center of the cross and a platform 3 is made to revolve on the same, a suitable anti-friction bearing 4 being interposed between the platform 3 and

the base. The platform has a plurality of radial partitions 6 rising therefrom, which latter are preferably arranged symmetrical so as to form sector-like chambers 7, the inner ends of which are defined by the walls 8 while the outer circumferential ends of the compartments are closed by preferably transparent plates 9 adapted to be slid downwardly in vertical grooves 11 in the partitions. The grooves are disposed in such a manner that portions 12 of the partitions project beyond the plates 9 allowing of the easy manipulation of the platform.

The cover 13 for the compartments is made of two concentric rings 14 and 16 and radial elements 17 holding the same in spaced relation. The spaces between the radial members 17 are filled with glass plates 18, the edges of which are accommodated in grooves 19 in the rings 14 and 16 and the radial elements 17. One of the spaces is left open as shown at 21, and through this opening access may be had to the compartment which happens to register with the opening. The cover is supported stationarily by means of legs 22 extending downwardly from the outer ring 16, the lower ends of the legs being fastened to the ends of the cross shaped base by means of screws 23. The legs are of sufficient length to hold the cover 13 in spaced relation to the top of the partitions 6.

The polygonal space 24 on the inside of the walls 8 is preferably covered by means of the plate 26 provided with a concentric projection 27 extending through the inner ring 14, and the vending device 28, described in my co-pending application, previously referred to, may be placed on this projection 27 so as to revolve with the compartments 7.

In use the device is placed on the counter over which goods are to be sold, in such a manner that the opening 21 in the cover is disposed so as to be accessible to the clerk selling the goods but not to the general public. The compartments are filled with candy of various kinds and the prices are preferably noted on the outer plates 9 in the manner indicated in the drawings. Any person desiring to select candy may freely revolve the platform by pushing on the projecting ends of the partition 6 so that the contents of each compartment may be viewed through the glass cover as well as through the transparent outer walls 9. The

contents of the compartment, however, are not accessible to the purchaser, and, if he wishes to buy candy out of any compartment, he has to refer to the clerk who will bring that particular compartment into registry with the opening in the cover and then withdraw the desired candy to hand it to the purchaser. It will be noted that the revolving of the platform with the compartments thereon does not affect the cover which remains stationary at all times and this is so even when the device illustrated in my prior application is used in connection with the present invention, since the latter device is merely placed on top of the member 27 so that it is caused to revolve with the compartments without, in any way, interfering with the stationary cover 13.

I claim:

26 In a vending machine of the character described, a base, a platform revolvable thereon having radial partitions forming

sectorial compartments on the same, transparent means for closing the outer ends of the compartments, a plate resting on the inner ends of the partitions having a reduced upward projection, a ring-shaped transparent cover surrounding the projection and overlying the rim of the plate having legs extending downwardly from its outer edge and means for securing the lower ends of the legs to the base for supporting the cover in spaced relation to the plate and the top of the partitions, the cover being formed with an opening allowing articles to be removed therethrough from any one of the compartments after the latter has been made to register with the opening and the plate projection serving as a support for a superstructure revolving with the platform while the cover remains stationary.

GEORGE H. KOSTER.
